UNITED STATES PATENT OFFICE.

WILLIAM HENRY HARISON EVERETT, OF NEWTON FALLS, OHIO.

ELECTRIC FIRE-ALARM.

No. 851,506.

Specification of Letters Patent.

Patented April 23, 1907.

Application filed September 22, 1904. Serial No. 225,544.

To all whom it may concern:

Be it known that I, WILLIAM HENRY HARISON EVERETT, a citizen of the United States, residing at Newton Falls, in the county of 5 Trumbull and State of Ohio, have invented a new and useful Improvement in Electric Fire-Alarms, of which the following is a specification.

This invention relates to an automatic 10 fire alarm in which the contacting plates are held apart through the medium of a glass bulb which is filled with a liquid readily expansible under a comparatively low temperature; the bursting of the bulb permitting 15 the contact plates to be forced together by means of a spring.

The object of the invention is to avoid the use of a metallic flux, the melting of which as in the case of plugs and fuse wires often results 20 in the molten metal flowing in such a manner as to cause a short circuit or to interfere with the proper working of the alarm, and the further object is a device of this kind which can be depended upon to send in 25 an alarm when the temperature reaches a certain point which is not the case with alarms using the ordinary fuse wires or plugs as the melting temperature of the said fuses vary with the composition and proportion 30 of the alloy of which they are composed and is usually from two to three times that of the temperature of boiling water.

My invention also consists in the novel 35 features of construction and combination of parts, hereinafter set forth, particularly pointed out in the claims and shown in the accompanying drawings, in which,

Figure 1 is a front elevation of my device. Fig. 2 is a side elevation of the device. Fig. 40 3 is an end view of the device as seen from below. Fig. 4 is a detail sectional view through the bulb.

In these drawings, A represents the wooden 45 base which may be secured to a wall by means of suitable screws, and which, adjacent its lower end, carries a transverse cross piece A', vertically slotted at A² and having a horizontal bore A³, intersecting the vertical slot A². The face of the board A, forming 50 the rear side of the slot A², has a concavity A⁴ formed therein. A glass tube B closed at its upper end is carried by the front face of the board A and at its lower end terminates

in a bulb B' which rests in the slot and in the concavity A⁴, the bulb being of thinner glass 55 than the remainder of the tube. The bulb and tube are filled with an expansible liquid as shown at B², and the tube is held in place by means of staples B³ and a transverse cleat C arranged at its upper end upon the base A. 60

Projecting forwardly from the cross piece A' are two horizontal, cylindrical bars D threaded at their outer ends and connected by a bracket D'. A rod E is loosely supported adjacent its outer end in an aperture 65 formed in the bracket D' and the inner end of the rod E bears on the bulb B'. A segmental metal plate E' is carried by the rod E and is suitably perforated and adapted to slide on the bars D. This plate E' has straight end 70 portions E² which form the movable contact plates of the device. A collar E³ is fixed on the rod E and a spring F is coiled around the rod E and bears at its outer end on the bracket D' and at its inner end on the segmental plate E' holding the same against the collar E³. Screws H are carried by the cross piece A' and when the plate E' is forced inward by the spring F, the end portions E² will 75 contact with the heads of the said screws H. Binding posts H' of the usual construction are mounted upon the cross piece A' and from these binding posts lead the circuit wires H². Connecting wires H³ extend from the binding posts to the screws H and are 80 held snugly under the heads of the said screws in the usual manner. Suitable nuts G are employed to hold the bracket D' in position and permit the adjustment of the said bracket in order to regulate the tension upon 85 the spring F.

It will be obvious that as long as the glass bulb B' remains intact the rod E will be held outward and the contact plates E² spaced from the heads of the screws H, but as soon 95 as the rise of temperature expands the liquid in the bulb and tube sufficiently to burst the bulb, the rod E can move inward and the spring F will force the segment E' also inward holding the contact plates E² against the screws H, thus completing the circuit 100 through the segment E' between the wires H².

Having thus fully described my invention, what I claim as new and desire to secure by Letters Patent, is:—

A device of the kind described comprising

contact points spaced apart, parallel bars, a bracket adjustable on and connecting said bars, a rod having an end portion loosely supported by said bracket, a segmental plate slidably mounted on the bars, said plate being carried by the rod, a spring bearing at one end on the bracket and at the

other end on the plate, a glass bulb resting against the inner end of the rod, an and expansible fluid in the glass bulb.

WILLIAM HENRY HARISON EVERETT.
